1 Claim. (Cl. 317—80)

This invention relates to delay shot firing counters for counting blasting number of explosives.

The blasting number of single shots and delay shots of relatively long delay intervals can be confirmed by counting the sounds of explosion with human ears, but in case of milli-second delay shots, it is impossible for the operator to confirm the blasting number by listening to the sounds of explosion, and consequently, misfired shot cannot be detected, with the fear of accidental explosion occurring later.

The present invention contemplates utilization of electric pulses that are generated at every blasting of explosives, for positively counting or registering even shots of extremely short delay, such as milli-second delay shots.

When an explosive is fired, a plus or minus electric pulse is generated without exception. Such a pulse can be taken out from between the leg wire of electric detonator and the ground in case of electric shot firing. According to the present invention, the above-mentioned electric pulse is introduced into the counting circuit through the firing lead wire. However, the electric pulses generated by firing of explosives are not even but different in individual explosions with respect to wave forms and durations, and their count cannot be taken as they stand, but each pulse should be converted to that of square waveform of a definite duration suitable for counting. Thus, according to the present invention, the delay shot firing counter essentially comprises a blasting machine, a primary and a secondary square wave generators, and a counter, all combined into a unity organization.

An object of the present invention is to provide a delay shot firing counter of such a small size and light weight that it may conveniently be portable, by utilization of transistor-type D.C.-D.C. converter giving constant output with low voltage dry cell battery as the power source for blasting machine.

Another object of the present invention is to provide a delay shot firing counter which always produces a constant output for blasting by employing in the blasting machine a constant voltage circuit comprising a transistor, a silicon diode, and a neon glow lamp.

Another object of the present invention is to provide a delay shot firing counter employing in the blasting machine an arc discharge tube having a cold cathode as the blasting switch, and a discharge resistance of a low resistance value as small as one tenth to one thirtieth of that in a conventional condenser type electric blasting machine, say 150Ω, and having an electric neutral point, whereby the current having been supplied for blasting is completely eliminated from all the circuit connected to the firing lead wire, before explosion of the first stage electric detonator.

A further object of the present invention is to provide a delay shot firing counter in which a primary square-wave voltage generating circuit is used for drawing out the electric pulse produced by the blasting of explosive from the neutral point of the afore-mentioned discharge resistance independently of the blasting voltage, and yet, independently of its polarity, the electric pulse produced by one explosion is converted without fail to a square-wave pulse of duration longer than the above-identified electric pulse.

A further object of the present invention is to provide a delay shot firing counter in which a secondary square-wave voltage generating circuit is used for converting the blasting voltage to a square-wave voltage of a duration longer than that of the blasting voltage, the above-mentioned square-wave voltage being used for clamping the afore-mentioned primary square-wave voltage generating circuit.

A still further object of the present invention is to provide a delay shot firing counter for counting blasting number of explosives by an electric counter operated by the square-wave output pulses of the afore-mentioned primary square-wave voltage generating circuit.

Particularities and details of the present invention will be made obvious from the following description of the invention, with reference to the accompanying drawing, in which the single figure is a circuit diagram showing one embodiment of the present invention.

Referring to the drawing, the delay shot firing counter embodying the invention as a whole is accommodated in a casing 1 provided with blasting output terminals 2 and 3, and an earth terminal 4. 5 shown by dotted lines, is a switch and interconnects a power switch 6 for the counter and a blasting switch 56 mechanically. Thus, when the switch 5 is operated to the ON position of the counter power source, the counter switch 6 is closed, and the power source 7 consisting of three dry cells in series operates a transistor-type constant-output D.C.-D.C. converter 8 for applying an anode voltage of D.C. 350 v. to the dekatron of a counter 9, to place the counter 9 in operating state. In addition, the power source 7 acts to place a transistor-type square-wave amplifier 10 and a transistor-type electric pulse amplifier 11 in operating conditions, and at the same time, places in standby states a primary square-wave voltage generating circuit formed by one shot multivibrator of 2.6 msec. interval of output square-wave, and consisting of transistors 12 and 13, resistances 14, 15, 17, 18, 19, 20 and 21, a m.p. condenser 15, and an electrolytic condenser 22; and a secondary square-wave voltage generating circuit formed by one short multivibrator of 8 msec. interval of output square-wave, and consisting of transistors 31 and 32, resistances 33, 34, 35, 37, 38, 39 and 40, a m.p. condenser 36, and an electrolytic condenser 41.

When the switch 5 is actuated to the position of blasting charge, the power switch 6 for counting system is held at the ON position, while the blasting switch 56 is operated to open its contacts 57-58 and to close its contacts 59, whereupon a switching transistor circuit commences to operate for converting the low voltage direct current of dry cells 62 to square-wave alternating current, the switching transistor circuit being consisting of switching transistors 60 and 61, the primary winding 64 of a convertor and boosting transformer 63, the contacts 57-59 of blasting switch 56, the dry cells 62, three in series, a transistor 66 forming the base circuit of switching transistors 60 and 61, resistances 67 and 68, a condenser 69, and a feedback winding 70 of transformer 63. The square-wave alternating current voltage thus produced is stepped up by the combined convertor and boosting transformer 63, and the output of its secondary high tension winding 65 is rectified to high tension direct current voltage by the voltage double rectification of a voltage doubler circuit consisting of silicon rectifiers 71 and 71', and m.p. condensers 73 and 72, whereby a blasting condenser 74 is charged up promptly.

When the terminal voltage of blasting condenser 74 thus charged has reached at 248 v. which is the control voltage of a constant-voltage silicon diode 75, that is 80% of the normal charging voltage, a controlled current of the contant voltage diode 75 flows through a resistance

76. A minute interval of time thereafter, or after about 1.5 to 3 seconds have elapsed from beginning of the charging, the terminal voltage of blasting condenser 74 reaches at substantially the normal voltage. At the same time, the terminal voltage of the resistance 76 also reaches at the firing potential of a neon lamp 77 (NE 68), whereupon the lamp 77 starts to discharge, and the discharge current of the same flows to the resistance 68 through a resistance 78. The resistance 68 is connected between the base and emitter of the current controlling transistor 66. The transistor 66 being connected in the base circuit of switching transistors 60 and 61, when the discharge current flows through the resistance 68, the electric potential of the base with respect to the emitter of the transistor 66 drops abruptly by about 0.15 to 0.20 v. Thereupon, the emitter-collector current of control transistor 66, or the base current of switching transistors 60 and 61 decreases, causing decrease in its collector current. Consequently, the electric energy of D.C. high voltage sent out to the D.C. high tension circuit is also made small instantaneously, resulting practically in termination of charging of the blasting condenser 74.

On the other hand, when the electric energy having been supplied becomes equal to the electric energy consumed in the D.C. high tension circuit, the aforementioned current increase in neon lamp 77, the lowering of base potential of the transistor 66, and the decrease in collector currents of the switching transistors 60 and 61, are terminated automatically, and the terminal voltage of blasting condenser 74 is kept to a substantially constant D.C. voltage, independently of regulation of voltage of the power source 62.

Next, if the switch 5 is returned to the blasting position, the blasting switch contacts 57-59 are opened and the blasting switch contacts 57-58 are closed, with the source switch 6 left at the ON position. Thereupon, the switching operation of transistors 60 and 61 stops, and the charge voltage of blasting condenser 74 is applied to the resistances 79 and 80. At this time, the potential difference between grid 83 and cathode 84 of a cold cathode arc discharge tube 81 (SP 902) being about 1.5 times its firing potential, main arc discharge takes place between its anode and cathode, thus supplying the energy charged in the blasting condenser 74 to the electric detonator connected between blasting output terminals 2 and 3, through the cold cathode arc discharge tube 81. Between the blasting output terminals 2 and 3, a provision is made for drawing out electric pulses produced by explosions of the explosives independently of the blasting voltage, and a discharging resistance 85 is connected, which is of a small resistance value as low as one tenth to one thirtieth of that for a conventional condenser-type blasting machine, say 150Ω or lower. This is for the purpose of completely eliminating the firing voltage from the blasting lead wires, electric detonator, and between the blasting output terminals 2 and 3, before explosion of the primary explosive.

The electric pulse generated by explosion of the explosive is applied through the blasting lead wires across the blasting output terminals 2, 3 and the earth terminal 4, and introduced into the electric pulse amplifier 11, through a combined amplitude limiter and band pass filter 51 and a transformer 50 having the primary and secondary windings insulated from each other. The electric pulse having been amplified in the amplifier 11 is applied to the resistances 29 and 30 connected across the secondary winding of transformer 49, as substantially the same potential pulses of opposite polarities with respect to the earth 87. The one shot multivibrator (the primary square-wave voltage generating circuit) of 2.6 msec. interval of output square wave, consisting of transistors 12 and 13, starts to operate at the time when the voltage applied to the resistance 29 or 30 is of positive polarity with respect to the earth 87, and its crest value is more than 200 mv. (corresponding to 150 mv. between ter-

minals 2, 3, and 4), and generates a single square wave pulse of 2.6 msec. duration for each input of the above-mentioned polarity and value. Thus, when the voltage applied to the resistance 29 is more than +200 mv. with respect to the earth 87, the pulse current flowing through condenser 27, semiconductor diode 23, condenser 16, and resistance 15 renders the transistor 12 OFF and the transistor 13 ON, and this condition is sustained for 2.6 msec. Upon elapse of 2.6 msec., the transistor 12 returns to ON, and the transistor 13 to OFF, and the one shot multivibrator assumes the standby state automatically. When the input electric pulse is of the opposite polarity, that is, when the voltage applied to the resistance 30 is more than +200 mv., the pulse current flowing through condenser 28, germanium diode 24, condenser 16, and resistance 15 operates the one shot multivibrator in the same manner as mentioned above. The resistances 25 and 26, and germanium diodes 23 and 24 are provided for the purpose that the electric pulse applied to the resistance 29 or 30 is supplied to the one shot multivibrator, only when the pulse is of positive polarity with respect to the earth 87, and the transistor 13 is OFF, in order to prevent erroneous counting caused by any wrong operation of the one shot multivibrator.

When the one shot multivibrator is operated as above-mentioned by the input electric pulse, there is a square wave output of about -4 v. in the resistance 14 connected to the collector of transistor 12. This square wave voltage is amplified by the transistor amplifier 10, and boosted by the transformer 48, to operate the counter 9 which counts the number of incoming pulses, that is, the number of explosions of explosives.

Further, when firing voltage is applied between blasting output terminals 2 and 3, it is also applied to the resistances 53, 54 and 55, and the insulating transformer 52, and a pulse voltage of about +1 v. momentary peak voltage with respect to the earth 87 appears on the secondary side 88 of insulating transformer 52 at the instant of application of blasting voltage. This pulse voltage acts through condenser 44 and germanium diode 42 to operate the one shot multivibrator of the secondary square-wave voltage generating circuit having transistors 31 and 32 as the active elements. The interval of output square wave of the above multivibrator is 8 msec. This 8 msec. square-wave pulse output of the secondary square-wave voltage generating circuit changes the -0.1 v. potential at the joint point of resistances 45 and 47 connected to the collector of transistor 31 to -1 v. abruptly, which acts through germanium diode 46 for rendering the transistor 13 of primary square-wave voltage generating circuit ON, thus clamping the primary square-wave voltage generating circuit in operating state during the operating period of the secondary square-wave voltage generating circuit, that is for 8 msec. from application of the blasting voltage. Consequently, during the above-mentioned period of time, the primary square-wave voltage generating circuit operates only one time, even if any other electric pulses would come thereto. As a result, the counters also do operate only one time during the same period, and this is to prevent erroneous counting caused by blasting voltage. Accordingly, the true number of firing of explosives is the count number of counter minus one in the delay shot firing counter of the present invention.

Further, according to the present invention, the delay shot firing counter comprises transformers 50 and 52 for insulating the blasting machine from the earth 87, which is connected to the earth terminal 4 through a high resistance 86 and a condenser 56. When it is not necessary to insulate the blasting machine from the earth 87, the terminals of high resistance 86 may be short circuited.

Test 1.—In 1.0-1.5 cm. deep of red earth, 100 g. ammonium gelatine dynamites were loaded one or two per hole, and all were connected in series with conventional milli-second delay electric detonators. A 15Ω parallel

resistance was externally connected with each detonator as input circuit for explosion pulse, and ground connections were made at two-metre distances from respective holes loaded with the dynamites.

Two rounds of tests were executed, with MS2-6 period detonators in the first test, and MS2-10 period detonators in the second. The explosions were effected and their number counted by a delay shot firing counter of the present invention. The results are shown in the table below.

Test No.	Detonators used	Number of blastings	Counted number	Number of explosions	Non-explored period
1 -----	MS2-6 period -----	5	5	5	0
2 -----	MS2-10 period -----	9	8	8	3rd

In the second test, for 9 detonators, 8 explosions were counted, showing one non-explosion.

Test II.—A hole of 15 m. length were perforated into a layer of coal of 2.4-3.2 m. and 180 g. ammonium nitrate explosives of low density were loaded therein. Double bridge type delay electric detonators of 30MS2-5 periods were employed. Ground connections were set to iron pillars in the gallery by magnets. Double bridge type electric detonator makes it unnecessary to provide external connection of parallel resistance as input circuit for explosion pulse. Distances between respective loaded positions and the ground connections were 1.3 to 2.8 m. The results are shown in the table below.

Test No.	Detonator used	Number of blasting	Counted number	Number of explosion	Non-explored period
1 -----	MS2-5 steps -----	4	4	4	0
2 -----	do -----	4	4	4	0
3 -----	do -----	4	4	4	0
4 -----	do -----	4	4	4	0
5 -----	do -----	4	3	3	4th
6 -----	do -----	4	4	4	0
7 -----	do -----	4	4	4	0
8 -----	do -----	4	4	4	0
9 -----	do -----	4	4	4	0
10 -----	do -----	4	4	4	0

Thus, the delay shot firing counter of the present invention can count the true number only of explosives which have actually exploded, any misfired explosive being detected without fail.

In addition, the delay shot firing counter embodying the present invention has, as the power source for the blasting machine, a circuit consisting of transistor 66, silicon diode 75, neon lamp 77, etc., so that a low potential battery may be utilized effectively, but there is no fear of misfiring due to shortage of output for blasting.

Further the delay shot firing counter of the present invention can promptly eliminate the blasting voltage from the blasting circuit because of using the blasting switch having a cold-cathode arc discharge tube and a discharge resistance 85 of lower than 150Ω between blasting output terminals 2 and 3. Thus, the delay shot firing counter of the present invention does never make miscount by virtue of blasting voltage or electric noise, if there were any short-circuiting or grounding of blasting lead wires.

Further according to the present invention, the electric pulses produced by explosions are taken out from the electric neutral point of the discharge resistance, and consequently, the electric pulse detecting circuit is never affected by the blasting voltage.

According to the present invention, it is also to be noted that the primary square-wave voltage generating circuit comprising transistors 12 and 13 as the active elements converts input electric pulses to square-wave voltages of

2.6 msec. duration which is longer than those of the input pulses. Consequently, even when the wave form of an electric pulse produced by explosion would be so complex that there may effectively be produced two or more electric pulses, the counter does never misoperate, but positively count one for one explosion.

In addition, according to the present invention, the limit of voltage for electric-pulse counting is established at ±150 mv. between the blasting output terminals (2, 3)

and the earth terminal (4). This voltage value is determined with a sufficient allowance with regard to experimental data, taking into consideration the fact that electric pulses produced by explosion of explosives are of varying voltage values to a large extent, so that miscounting of number of explosions is fully prevented.

It is also to be noted that, according to the present invention, the secondary square-wave voltage generating circuit comprising transistors 31 and 32 as the active elements is provided for converting blasting voltages into a square-wave pulse of 8 msec. duration which is longer than those of the blasting voltages, and primary square-wave voltage generating circuit is clamped with the output square-wave voltage of said secondary square-wave voltage generating circuit. As a result, the primary square-wave voltage generating circuit can operate once only during the 8 msec. duration from the application of blasting voltage, thus preventing the counter from misoperation by virtue of electric noises.

What I claim is:

A delay shot firing counter comprising a blasting machine formed by an electric supply source consisting of transistor-type D.C.-D.C. convertor of a constant output voltage, a circuit of a transistor, a silicon diode and a neon lamp to obtain a constant voltage output for blasting, a blasting switch consisting of a cold cathode arc-discharge tube, and a discharge resistance lower than 150Ω provided at the output thereof, a circuit so arranged that electric pulses produced by explosion of explosives are taken out from the electric neutral point of said discharge resistance, a primary square-wave voltage generating circuit for converting each of said electric pulses into a single square wave pulse of duration longer than said first mentioned electric pulses, a secondary square-wave voltage generating circuit for converting a blasting voltage into a square-wave voltage of duration longer than that of said blasting voltage, for clamping said primary square-wave voltage generating circuit, and a counter operated by the square-wave output pulses of said primary square-wave voltage generating circuit for counting number of explosions of the explosives at the same times with blasting of said explosives.
